UNITED STATES PATENT OFFICE.

HORATIO WHITING, OF NEW YORK, N. Y., ASSIGNOR, BY MESNE ASSIGNMENTS, TO
UNDERWOOD COMPUTING MACHINE COMPANY, OF NEW YORK, N. Y., A CORPO-
RATION OF NEW YORK.

COMBINED TYPE-WRITING AND COMPUTING MACHINE.

1,308,133.

Specification of Letters Patent.

Patented July 1, 1919.

Application filed March 13, 1915. Serial No. 14,061.

To all whom it may concern:

Be it known that I, HORATIO WHITING, a citizen of the United States, residing in New York city, in the county of New York 5 and State of New York, have invented certain new and useful Improvements in Combined Type-Writing and Computing Machines, of which the following is a specification.

10 The invention relates to a combined type-writing and computing machine of the Underwood-Hanson type, and more especially to the control of the character of computation carried on by the computing mechanism from the computing mechanism itself.

In a machine of this character, computing is generally carried on in a number of zones, and it is desirable to change the character of computation from zone to zone to correspond with the requirements of the particular work being done. For example, it may be desired to add an item in one or more computing heads or totalizers in one column or zone, and in the next column or zone subtract an item in the same or another computing head. It may be desirable also to simultaneously add and subtract the same item for the same zone in two or more different computing heads.

20 For a given type of work a given sequence of different computations is generally repeated over and over again for each successive line. This requires then a predetermined sequence or succession of different types of computation for one or more computing heads. It is desirable that it be controlled automatically so that the attention of the operative will not be called away from the work at hand, so that it will be

25 merely necessary to strike the numeral keys, copying the numbers in the various columns or zones where they will be automatically typewritten and computed as required.

A feature, therefore, of this invention is to provide a plurality of computing heads, in the present instance three being shown, with an automatic arrangement for controlling the states or character of computation carried on by said computing heads for a series of zones or columns, and according to a predetermined sequence or order. Inasmuch as the general operator for the computing mechanism is operated each time a

computation is run up, and may be operated for every computing zone or column, use 55 is made of the general operator to actuate or drive the state-controlling mechanism.

The state-controlling mechanism may be arranged and rearranged to suit the number of zones or computing columns to be used 60 for any given character of work. In the present instance, it consists of a control disk for each computing head, having a series of slots therein, one for each zone. In these slots may be placed tappets differently extending for subtracting and for neutral, a blank space being left when it is merely intended to add in a given zone for a given computing head. The series of disks are mounted for a common rotation step by step 65 corresponding to the change zone by zone for each actuation of the general operator. This enables a change in state if desired in one of the computing heads or all of them after each computation is run up. The 70 disks will be the same for all computing heads for a given character of work. The number of slots in the disks used will be the same as the number of computing zones or a multiple thereof. The disks are driven so from the general operator variable amounts inversely proportional to the number of zones so as to complete a rotation with the completion of a cycle of zones. Thus if there are to be nine zones, the disks having 75 nine slots will be used, and will be advanced one-ninth of a revolution at each actuation of the general operator. This is accomplished by providing an adjustable striker or tappet on the general operator which may 80 be variously placed so as to give different driving movements of the different disks, to wit, the nine-slot disks and a ninth of a revolution for nine zones; the eight-slot disks and an eighth for eight zones; the seven-slot 85 disks and a seventh for seven zones, and so on.

By the use of common denominators, the number of different types of disks may be limited to five, having, respectively, nine, 100 eight, seven, six, and five slots. If a lesser number of zones is required, say four, every other slot may be used in the eight-slot disks, and the series of disks given a quarter of a rotation for each operation of the general 105 operator, instead of an eighth. If only

three zones are needed, either the nine-slot disks may be used, using every third slot, or the six-slot disks used, and rotating the disks a third of a revolution at a time.

5 The rotation of the disks is controlled from the general operator. There is provided a differential driving connection so as to drive the series of state-controlling disks step by step with each operation of the general operator, variable amounts according to the number of zones for a given series of computing operations.

In order that the state-controlling mechanism may indicate which zone is in play at any given time, a zone-indicator is provided, which will be driven from the state-controlling mechanism. Inasmuch as, however, the state-controlling mechanism varies in its extent of movement for different numbers of zones in a series of predetermined computing operations, the drive is arranged so that it will move the zone-indicator a step for each step of movement of the zone controller no matter how great the magnitude of the latter movement may be. This, then, will indicate the successive zones in action whether there be one, two, five, or a greater number. When the state-controlling shaft has completed its rotation and thus completed the series of states which it controls for a given group of computing operations, the zone-indicator will be automatically tripped and returned to its starting position by means of a tension spring so that it will be free to come in synchronism with the state-controlling mechanism as the latter starts a new series of predetermined computing states.

Under certain circumstances it is not desirable to have the state-controlling-mechanism operate every time the general operator is actuated. One instance is where an error has been committed and it is desired to actuate the general operator, as, for example, when one or more of the computing units are set for subtraction. The error key is so connected that when actuated it will silence the drive to the state-controlling-mechanism, so that the latter remains in *status quo*, whereby the computing units will remain in the same states for the zones for which they were previously set. The drive to the state-controlling-mechanism can also be silenced at will in case it is desired to prevent a change in the state-controlling-mechanism at times other than when the error key is operated.

Other features and advantages will hereinafter appear.

60 In the accompanying drawings,

Figure 1 is a vertical section taken from front to rear, with parts omitted for the sake of simplicity, and showing the general relation of the typewriting mechanism to the computing mechanism.

Fig. 2 is a horizontal section showing the three computing units in a general way and the common mechanism for selectively setting up a computation for any or all of them.

70 Fig. 3 is a vertical section from front to rear through the computing casing, showing one of the computing units as set for subtraction by the state-controlling disk therefor.

75 Fig. 4 is a vertical section taken from front to rear showing the driver for the state-controlling mechanism as having advanced its full length forward idly and about to be returned to actively drive the state-controlling mechanism, which latter is set for but two computing zones. The subtraction-setting mechanism is shown as having been over-primed and caught by a supplementary latch so as to be caught subsequently by the latch control from the state-controlling mechanism after the general operator has come to rest.

80 Fig. 5 is a detail view of one of the tappets which has a lug which may be projected to one side or the other according to whether it is to control a subtracting or a neutral operation for the computing unit of the disk in which it is located.

85 Figs. 6 and 7 are views of a six-slot disk which may be used to control, six, three, or two computing zones.

90 Fig. 8 is a detail vertical section showing the means for detachably locking a disk on the controller shaft and the method of placing one of the tappets in one of the slots in the disk.

95 Fig. 9 is a detail section showing the one-way-driving clutch connection to the state-controlling shaft.

100 Fig. 10 is a vertical detail section taken from front to rear, showing how the state-controlling mechanism may be silenced at will, or from the error key, and in this particular instance the manual lever is shown to have actuated to silence the state-controlling mechanism.

105 Fig. 11 is a view similar to Fig. 10, except that the error key has been actuated to correct an error and to silence the state-controlling mechanism.

110 Fig. 12 is a vertical section taken from front to rear, showing the parts of one of the computing units in normal position ready to perform an adding operation.

115 Figs. 13, 14 and 15 are details of the mechanism for silencing the drive to the state-controlling mechanism, so as to prevent a change therein.

120 Fig. 16 is a skeleton perspective view showing the relation of the various control sets of the state-controlling mechanism to the controlling elements of the three computing units or heads, and the relation of all control sets with the common drive.

Fig. 17 is a detail section showing the means for translating the variable step movements of the state-controlling shaft to the zone indicator.

5 Fig. 18 is a detail section showing the clutch which forms the connecting link of part of the mechanism shown in Fig. 17.

Fig. 19 is a vertical section taken at right angles to Figs. 17 and 18, showing the same 10 mechanism and showing the clutch held in its active position so as to form a positive driving connection.

15 Figs. 20 to 23 in order show successive positions of the driving mechanism from the state-controlling mechanism to the zone-indicator, whereby different extents of movements of the former may be transmitted into a given extent of movement of the latter, and thus turn up a new zone for each step in 20 a cycle of movements of the state-controlling mechanism even though the latter vary for different numbers of zones in a cycle.

Fig. 24 is a view of the parts shown in 25 Figs. 20 to 23, and illustrating how the zone-indicator is released at the end of a cycle of computing zones to enable the same to return automatically to its initial position corresponding to the first computing zone.

Fig. 25 is a rear view in elevation partly 30 in section, showing the means for silencing the various computing units.

Fig. 26 is a diagrammatic assembled view 35 of the several different types of controlling disks which may be used in the state-controlling mechanism, they having in the present instance anywhere from five to nine slots to take care of anywhere from one to nine zones.

The invention is shown as applied to the 40 well-known Underwood-Hanson combined typewriting and computing machine in which numeral keys 1 depress key-levers 2, to rock bell cranks 3, so as to swing type-bars 5 up rearwardly against the front side 45 of a platen 6 mounted to rotate in a carriage 7. The carriage 7 has the usual step-by-step feeding movement under the control of an escapement mechanism indicated in general at 8, which is actuated at the operation of 50 any of the keys by means of heels 9 provided on all of the type-bars. The carriage 7 may also be jumped from column to column or zone to zone by tabulating mechanism indicated in general at 10.

55 The numeral keys 1 in addition to controlling the typewriting mechanism, control the computing mechanism, and for this purpose, each of the numeral keys from "1" to "9" is provided with a pendent thrust link 60 11, arranged to engage an arm 12 on a rock shaft 13. There is one of these arms 12 and rock shafts 13 for each numeral key from "1" to "9", and in the present instance, they each operate a master linkage 14.

65 In the present instance three computing

units are provided including computing heads A, B and C (Fig. 2). Each computing head is provided with a series of computing wheels 15, which are arranged to exhibit the numbers run up thereon through 70 sight openings 16 in the computing casing 17. The wheels 15 are driven in the usual manner through the intermediary of one-way-acting gears 18 driven by racks 19 on denominational or order bars 20. The order bars 20 are provided with the usual pins 21 settable to determine the extent of movement of their respective order bars. The pins 21 are settable indirectly from the master linkages 14 at the striking of related 80 numeral keys 1. These pins may be set when adding according to the direct values of the numeral keys actuated, and when subtracting according to the complementary values.

There are a number of computing units, 85 in this case, three, and it is sometimes desirable to compute on one computing unit while one or both of the others may be silent, and it is also sometimes desirable to add on one computing unit while subtracting on another computing unit, while the third computing unit may either be subtracting or be silent. To enable this variation in the activity of the several computing units, they are each provided 90 with a secondary set of setting linkages or indexing devices 22, which may be rendered subservient to the master set of setting linkages 14 in one way or another according to the character of computation desired for 100 any particular computing unit. This system of a master set of setting linkages and a plurality of individual subservient sets of setting linkages in itself forms no part of the present invention, so that details of it 105 will not be described at this point; reference may be had, however, to a co-pending application of Richard M. Becker, No. 782,307, filed July 31, 1913, for details of the working of the same.

110 It will be sufficient, therefore, to say that each secondary setting linkage includes a series of shafts 23 (Fig. 2), which are provided with two sets of arms 24, each set alternating in its action for addition and subtraction respectively. When adding, the arms connect up the secondary linkages to the master or primary linkages in such a way that the direct values of the numeral keys actuated will be set up in the nest of 115 pins 21 for corresponding movements of their associated denominational bars 20. When subtracting, however, the other set of arms comes into play and connects up the master setting linkages with the secondary 120 set of setting linkages for a particular computing unit, so that the pins will be set to give movements of the rack bars 20 according with the complementary values of the 125 numeral keys actuated, using nine as a base. 130

To effect the change in the activity from one of the series of arms 24 to the other series of arms 24, for each individual computing unit, the shafts 23 are moved bodily in unison by a shifter 25. There is one of these shifters 25 for each computing unit, so that the change is individual for each computing unit.

No matter which way the secondary setting linkages 22 are connected up to the master setting linkages 14, the nest of pins 21 normally lies beyond the range of the secondary setting linkages 22, but are brought 10 denomination by denomination within range 15 thereof to correspond with the particular denomination or order being typewritten in.

To thus synchronize the action of the computing mechanism to that of the typewriting mechanism, there is adjustably 20 mounted on the carriage 7, at zonal intervals, tappets 26, which normally remain in a depressed position out of reach of a series 25 of nests of jacks 27, one nest for each computing unit A, B and C. When, however, one or more of the tappets come into a computing zone or zones, a zone-controlling 30 roller 28, one for each computing unit, engages a follower roller 29 and cams the tappet 26 up to a position such that a one-way- 35 acting dog 30 thereon will engage and raise each one of the jacks 27 *seriatim*. The jacks 27 are pivoted intermediate their ends so that their rear ends will depress thrust links 31 to rock levers 32 operating transposition 40 linkages 33, which in turn operate the denominational or order members 20 one by one to bring the pins 21 thereon within the range of the secondary setting linkages 22. The transposition linkages are of a type 45 such that the successive operations of the jacks 27 which progress from right to left corresponding with the travel of the carriage 7, will be inverted to operate or bring into action a series of denominational order 50 members 20 successively from left to right to correspond with the progression of the computation.

Each of the zone controllers 28 is 55 floatingly mounted by means of a frame 34 on a shaft 35. They are normally held in a position to operate the tappets 26 as they come along into the range or zone of a computing unit, by means of springs 36. This then would give, under normal conditions, an activity 60 of each computing unit for every zone, for which provision has been made by the placement of one of the tappets 26. This would mean that all computing units would add if all zone controllers 28 were in action 65 and none of the computing units were set for subtraction.

It is desirable, however, at times to silence or neutralize one or more of the computing units. To do this, each of the controllers 28 is movable against the tension of its spring

36, to an inactive position in which no matter whether a tappet 29 comes into the field of the jacks 30, it will not be raised to operate them. For this purpose, each of the frames 34 is provided with an arm 37 connected 70 to be operated by a link 38 (Fig. 25). Each link 38 is connected to be rocked by a bell crank 39 (Fig. 16), which in turn is operated by a non-add or neutralizing bar 40. The bars 40 may be operated by 75 hand, but are also operable automatically according to a predetermined sequence in a manner to be presently described.

To go back to the subtraction-setting mechanism, for each of the computing units 80 A, B and C, there is provided one of the shifters 25, which, it will be remembered, changed the position of the shafts 23 to rearrange the operating relation of the secondary linkages from the primary linkages, 85 so that the former would set the pins 21 according to the complementary values of the numeral keys actuated. The shifter 25 in each case is provided with an arm 41, which in turn is operated by an arm 42 of a bell 90 crank 43, having a pin-and-slot connection 44 with a subtraction bar or rod 45. It will be noted that the relation of the arms 41 and 42 is such that they form a toggle, which when the subtraction rod 45 is forced rearwardly, will lock in the manner shown in Fig. 3, holding the shifter 25 for the associated computing unit in its subtraction-setting position. The various other functions essential to a complementary subtraction 100 are performed at the same time that the shifter 25 is actuated. For example, the "9" pins on all orders of a computing head set for subtraction, are set.

To do this, each of the subtraction rods 105 45 is provided with an act-and-trip mechanism 46, similar to that shown in a co-pending application of John N. Thornton, No. 769,132, filed May 22, 1913 (now Patent No. 1,283,360, dated October 29, 1918), which 110 simultaneously raises all of the denominational or order bars 20 for the computing units, and sets the "9" pins by a depression of a bail 47. The action is such that the bail 115 sets the "9" pins, and then returns to a cleared position as the subtraction bar 45 goes to its completely actuated position. The subtraction bar 45 in each instance is operated by a spring 48, which is normally under a tension tending to operate its associated subtraction bar and the mechanism connected thereto. However, such action is generally prevented by a latch 49, which engages a notch or shoulder 50 in the associated subtraction rod. When it is desired 120 to have a particular computing unit subtract, this latch 49 is tripped, permitting the spring 48 to act and set the mechanism for subtraction. The latch 49 is provided with an arm 51 operable by a subtraction key 52, 130

which extends to the front of the machine, where, if desired, it may be operated manually.

All of the computing units A, B and C are driven by a common general operator 53, which is arranged to drive the order members 20 of such of the computing units as are active, and amounts corresponding to the particular pins set up thereon, whether these pins have been set for addition or subtraction. The general operator acts as in the case of application No. 782,307 above mentioned, and is provided with a cross bar 54, which on the forward stroke of the general operator, engages all of the pins which happen to be set, and drives the rack bars 20 corresponding amounts. This motion is transmitted in the usual way to the computing wheels 15. If any computing unit is subtracting, such of the computing wheels as have not had a digit struck therefor, will be rotated nine points, and then have "1" carried thereto, so as to give the correct subtraction by a complementary action. At the operation of the general operator 53, such of the springs 48 as may have acted to set the associated computing unit for subtraction, will be re-tensioned, and the subtraction mechanism returned to its normal dormant position so that the associated computing unit may add at the next actuation of the mechanism, if not otherwise rendered dormant or again set for subtraction.

To restore the subtraction rod 45 and the associated parts so that the same will be primed to come into play for a new subtraction operation, the cross bar engages a lug 55 provided on this subtraction rod 45, and draws the same forward against the tension of the spring 48 near the end of the forward movement of the general operator 53. The subtraction rod 45 is over-set in each instance a slight amount for purposes to be explained hereinafter, in which over-set position it is caught by a supplementary spring-pressed latch 56, which engages a notch or shoulder 57 provided in the associated subtraction rod 45. This action enables the normal or main latch 49 to be in its disconnected position, while the supplementary latch 56 holds the subtraction rod 45 until such time as the normal latch 49 can come into its locking position. This will occur at the end of the return stroke of the general operator, at which time the supplementary latch 56 may be tripped by the cross bar 54 coming into engagement with an arm 58, and releasing the latch 56 against the tension of its spring 59, which normally tends to draw it into an effective position.

The general operator performs the many functions usual in this type of machine, which will not be gone into in detail, and for further description of which reference may be had to an application of Hans Han-

son, No. 626,550, filed May 11, 1911 (now Patent No. 1,278,812, dated September 10, 1918). The general operator may be driven in any suitable way either by hand or by a motor 60, from which it is normally disconnected by a broken train of gearing including a single-acting clutch 61 of the type shown in the patent to Frederick A. Hart, No. 1,190,233, dated July 4, 1916. The action of this mechanism will not be gone into in detail. Sufficient is to say that if a stop 62 is raised clear of a lug 63, the clutch 61 will automatically connect itself for one revolution to give one back-and-forth cycle of movement of the general operator 53. The stop 62 may be manipulated in any suitable way, as by means of a lever 64 operated by a link 65, which may be operated by a key 66.

It has thus far been shown how a plurality of computing units may be subservient to a single set of numeral keys to such an extent that any or all of them may be called into action at the same time to compute the same numbers, and to compute them either for addition or for subtraction. Inasmuch as for a given piece of work, the activity and character of activity carried on by the several computing heads will be the same and in a predetermined sequence for each line or group of computations, it is hence a feature of the present invention to relieve the operative of the necessity of setting each computing unit for its different states every time there is a change made, and to do the same automatically. Inasmuch as the general operator is generally and may at all times be operated for each new computing zone or column, use is made of the general operator to advance step by step a state-controlling mechanism, which for each new zone is arranged to determine the individual states, that is, the activity and character of activity of each computing unit therein.

It has been shown how the computing units are normally in a condition to add, and how they may be individually set for subtraction by an operation of the associated subtraction rod 45. It has also been shown how each computing unit may be individually silenced for any particular zone by moving its zone controller 28 to a depressed and inactive position.

Inasmuch as the ultimate control for the subtraction-setting mechanism in each instance is its subtraction key 52, and the ultimate control for the neutralizing or silencing mechanism is the non-add bar 40, the automatic state-controlling mechanism is arranged to operate these parts according to a predetermined sequence for the several computing units as the computing and typewriting mechanism advances zone by zone. In the embodied arrangement for doing this, a state-controlling shaft 67 is provided, which is given an advancement or fractional turn for each

change in zone, so that at the end of a cycle of zones or computing operations, it will have returned to its original starting point. The magnitude of the step of advancement 5 of the shaft 67 will vary according to the number of zones in a cycle. The cycle may be a line of writing and computing, which may include anywhere from one to nine columns or zones in the present embodiment of 10 the machine, although the number of zones may be increased if desired.

On the shaft 67, there are provided a plurality of individual controllers in the form of disks 68, one for each computing unit. 15 The disks 68 have a number of slots 69 corresponding to the number of zones or a multiple thereof which are to be used for any given computing work. For example, if there are nine, eight, seven, six, or five computing zones, the disks will have, respectively, nine, eight, seven, six, and five slots. If zones of lesser number are to be provided for, the same disks may be used according to 20 the number of zones. That is, if four zones are needed, the eight-slot disks may be used; if three zones, the six-slot or nine-slot disks; if two zones, the eight-slot disks, and one zone, any of the disks. The shaft 67, however, is rotated according to the number of 25 zones, and not necessarily according to the number of slots 69 on the disks.

The slots 69, while they indicate the stopping or zonal points of the state-controlling mechanism, as a whole are for the purpose 30 of providing locating and attaching points for tappets 70, which are arranged to operate the subtraction key 52 or the non-add key or neutralizing rod 40. The tappet 70 may be formed as shown in Fig. 5, with an 35 extension 71 projecting from one side thereof. If this tappet is placed in a slot 69 with the extension 71 projecting from the left, as in Fig. 16, in connection with computing unit C, it will engage a pin 72 when 40 the computing mechanism comes to the zone corresponding to this tappet, and will rock a bell crank 73, so that an arm 74 thereof will engage a pin 75 on the subtraction key 52 and force the same rearwardly against 45 the tension of a spring 76. The subtraction key 52 when moved rearwardly in this manner, it will be remembered, will trip the 50 latch 49, permitting the spring 48 to operate to set the mechanism of the associated 55 computing unit for subtraction.

If one of the tappets 70 is set in the reverse position to that just mentioned, with the extension 71 projecting toward the right, as the tappet shown on the disk 68^b for the 60 computing unit B, it will be in a neutral controlling position to engage a pin 77 on a bell crank 78, one arm 79 of which is connected to force rearwardly the neutral rod 40, thereby withdrawing the zone control 65 lever 28 for the particular computing unit

having a tappet so set, thereby neutralizing or silencing that computing unit for the zone corresponding to the slot in which the tappet 70 is set for neutral.

Inasmuch as there is a disk 68 indicated 70 at 68^a, 68^b and 68^c, for each of the computing units A, B and C, the tappet 70 will be set in the several slots thereof in different arrangement or not at all according to whether it is desired to have subtracting or 75 neutral conditions, or an adding condition. That is to say, if there is no tappet at all in the slots the computing unit will add when the disk brings such a slot around to the active point corresponding to the computing 80 zone or column in action. If, however, the tappet 70 is set projecting toward the left, when it comes around to the active point, it will operate the associated lever 73 to trip the associated subtraction-setting mechanism for that particular computing unit. If, however, the tappet 70 is set with the extension projecting toward the right, it will 85 control a neutral condition of the associated computing unit when this tappet comes 90 around to the active point corresponding to the computing zone *in esse*.

In order that the disks 68 may be readily changed in case the character of work is desired to be changed, they are detachably 95 mounted on the shaft 67 and can be substituted one for the other. For this purpose, each of the disks 68 is provided with a slot 80, by means of which it may be slid on and off squared portions 81 of the shaft 67. To 100 detachably lock each disk in position, a yielding spring-pressed ball latch 82 is provided, which engages a slit or socket 83 provided at a proper point in the disk. The casing 17 is provided with a hinged cover 84 105 to permit access to the state-controlling mechanism either to change the relation of the tappets 70 or to change the disks 68 as a whole and substitute other disks with greater or less numbers of slots for different 110 numbers of computing zones.

To vary the drive of the shaft 67 to correspond with the number of zones and thus slots 69, the shaft 67 is driven from the general operator at each operation thereof, 115 and a fraction of a revolution corresponding to the number of zones. To do this, the shaft 67 is provided with a gear 85 meshing with a rack 86 on a bar 87. The bar 87 is normally held in its normal position by a 120 spring 88. The movement of the bar 87, under the impulse of the spring 88, does not, however, cause the gear 85 to drive the shaft 67, as this gear has a one-way-acting ball-clutch connection 89 (Fig. 9), which permits 125 the gear 85 to rotate idly with respect to the shaft 67 on the forward stroke of the bar 87, but to drive the latter on the rearward stroke. The rearward stroke of the bar 87 varies with the number of zones. That is to 130

say, the general operator passes idly by the bar 87 on its forward stroke, and operates the same on its rearward stroke, and then escapes, permitting the spring 88 to return 5 the bar 87 to its normal position.

To get the variable drive of the bar 87, it is provided with a series of slots 90°, 90°, 90°, 90°, 90°, 90°, 90°, 90° and 90°, corresponding, respectively, to the number of zones to 10 be used, and also inversely to the fraction of driving movement of the shaft 67 by the bar 87. That is to say, if we place a tappet 91 in the 90° slot, the shaft 67 will be driven a ninth of a revolution. If the tappet is 15 placed in the 90° slot, it will be driven an eighth of a revolution; in the 90° slot, a seventh of a revolution, and so on down to a complete revolution when placed in the 90° slot. The first few of the slots 90°, 90°, 90°, 20 are staggered with respect to each other because of their close proximity. The tappet 91 lies in the path of movement of a dog 92 pivotally mounted on one of the side bars of the general operator 53. This dog 92 is normally held down to an active position by a 25 spring 93. As it moves forward, however, the tappet 91 merely carries it up idly without being driven therefrom. On the return stroke of the general operator, however, the 30 end of the dog 92 comes into engagement with the tappet 91 and moves the rack bar 87 rearwardly against the tension of the spring 88. The amount of movement depends on the position of the tappet. If it is 35 far forward in the 90° slot, it will move the rack bar 87 sufficiently to drive the shaft 67 a complete revolution. If, however, it is in the 90° slot away back, it will merely move the rack bar 87 a sufficient distance to rotate 40 the shaft 67 a ninth of a revolution. The dog 92 is tripped automatically by a stationary cam or disconnector 94 engaging a pin 95 provided on the dog. This permits the tappet 91 to escape therefrom when the 45 requisite rotation of the shaft 67 has been obtained.

Under certain conditions it may be desirable to silence the state-controlling mechanism. One of these conditions is when an 50 error has been committed, and it is desired to correct this error and then compute again in the same zone. This correction may necessitate an actuation of the general operator as in case one of the computing units 55 is set for subtraction and has to be re-set. Arrangement is therefore made whereby when the error key, indicated at 96, is operated, it will silence the drive to the state-controlling mechanism so that there will be 60 no change in the setting of the states of the computing units.

The error key acts in the usual manner common to this type of machine, to rock a bell crank 97, which actuates, among other 65 things, a pin-restoring plate 98. The bell

crank 97 is secured to a shaft 99 and rocks the same. This shaft 99 is provided with an arm 100 connected to a throttle 101 having a hook 102 to engage over a lug 103 provided on the dog 92. The throttle 101 can 70 also be operated independent of the error key 96, by means of a handle 104, which has a lost-motion connection 105 with the throttle 101, permitting the error key to operate the throttle without disturbing the 75 handle 104. When the throttle 101 is operated from either of these sources, the hook 102 draws on the lug 103, so as to rock the dog 92 about its pivot until a latch 106 is forced by a spring 107 into engagement with 80 the pin 95 provided on the dog 92, so that the dog 92 will be held in its raised position free and clear of the disconnector 94, and beyond reach of the tappet 91 on the bar 87. It will thus be seen that when the dog 92 85 is held in this position, the general operator can be reciprocated without driving the rack bar 87, and thus without operating the state-controlling mechanism, so that there will be no change in the setting of the states 90 of the various computing units.

On the return of the general operator, the latch 106 is automatically tripped to release the dog 92 and permit it to come down to a resting position on the disconnector 94, 95 where it will once more be capable of coming into play on a subsequent action of the general operator. The tripping of the latch 106 is taken care of by a one-way-acting trip 108, which pivots yielding against the tension 100 of a spring 109 during the forward motion of the latch 106, but on the return motion of the latch 106 with the general operator, a pin-and-stop connection 110 comes into play to hold the trip 108 rigid. 105

In order to insure an actuation of the general operator when the silencing mechanism for the state-controlling mechanism is brought into play either from the error key or the hand lever 104, there is provided on 110 the shaft 99, a starting arm 111, having a one-way-acting dog 112 thereon, which is rigid with the arm 111 during a down stroke, so as to operate the stop-controlling lever 64. The dog 112 pivots idly against 115 the tension of a spring 113 on the return stroke of the arm 111, so as to permit it to clear the lever 64.

Inasmuch as the state-controlling mechanism is preferably placed within the computing casing 17, where it cannot be readily tampered with or altered, it is desirable to have some outside means of indicating what particular zone in a given series of computing zones or columns is in service at any 120 particular instant. For this purpose, there is loosely mounted on a portion of the shaft 67 which extends outside of the casing 17, an indicator 114 (Figs. 16 to 24), in the form of a wheel having a series of digits from "1" to 130

"9" on the periphery thereof, corresponding to nine computing zones. The indicator 114 does not move exactly with the shaft 67, as the latter sometimes makes a complete revolution for one or two zones and sometimes for nine zones, while the indicator must move step by step according to the zones and not according to the magnitude of movement of the shaft 67.

10 To obtain this differential movement, the indicator 114 is provided with a one-way-acting ratchet wheel 115, which is to be engaged and driven by a definite throw lever 116 having a spring-actuated pawl 117 to engage the ratchet wheel 115. Normally, the definite-throw lever 116 and its pawl 117 is clear of the ratchet wheel 115, as in Fig. 24. It is arranged, however, at a rotation of the shaft 67, to be brought into engagement with the ratchet wheel 115, and advance the indicator 114 always the same amount, that is, the distance between two adjacent digits on the periphery thereof, as between "1" and "2," "2" and "3," and so on.

15 20 The advancement of the indicator 114 is against the tension of a spiral spring 118, which is secured at one end to the indicator 114 and at the other end to a fixed bracket 119. At each advancement of the indicator 114, it is caught by a spring-pressed detent 120 acting in a notched or lock wheel 121 formed on one of the side faces of the indicator 114.

25 30

To translate the variable extents of movement of the shaft 67 into a definite movement of the indicator 114 and the lever 116, an actuator 122 is arranged to engage and operate the lever 116 at each movement of the shaft 67. The actuator 122 is shown in the form of a lever encircling a reduced portion 123 of the shaft 67, and having a ball clutch 124 to engage a cone clutch 125 provided on the shaft 67. One end of the actuator 122 is held against yielding by working in a guideway 126. The other end is normally urged so as to bring the ball clutch 124 into engagement with the cone clutch 125, by means of a spring 127. As the shaft 67 starts to rotate, the clutch 124 and 125 causes the actuator 122 to swing with the shaft 67, bringing a curved surface 128 of the actuator into engagement with an arm of the lever 116, so as to drive the latter. When the work is put upon the actuator 122 in this way, a guide-block 129 comes into play to prevent the actuator from squirming away from the lever 116, and thus preventing disengagement of the clutch elements 124 and 125. After the actuator 122 has given the lever 116 a definite throw, the former escapes from the latter, permitting the latter to return under its spring 130.

In order to return the actuator 122 to its starting position after it has driven the lever 116, it comes into engagement with a cam

131, which first yields against the tension of a spring 132, and then comes against a stop 133, so as to positively force the actuator 122 in the direction of the axis of the shaft 67, so as to disengage the ball clutch 124 from the cone clutch 125. When this is accomplished, the driving force being eliminated from the actuator 122, the latter is snapped by the spring 132 with the cam 131 to a position such that the actuator 122 will come in back of the guide-block 129, which guide-block at this point is provided with an inclined surface 134, so that the spring 127 will force the actuator still farther to its disconnected position, so that the latter can complete its movement without further driving the actuator 122. The guide-block 129 is formed to coöperate with a guide 135, so as to return the actuator 122 to its starting position after the shaft 67 has ceased to rotate, so that it will be once more clutched to the shaft 67 ready for a subsequent operation. A retarder 136 permits a quick action on the forward stroke of the actuator 122, but prevents a quick action on the return stroke, so that the clutch elements 124 and 125 will not reengage until the shaft 67 has ceased its rotation.

Inasmuch as the shaft 67 completes a cycle of state-controlling actions when it completes a revolution, it is desirable to return the indicator 114 at this time to a starting position so that it will always be in synchronism with the state-controlling mechanism whose zones it points out. To do this, the shaft 67 is provided with a tripping ring 137, which when the shaft comes to a home or starting position, engages a cam surface 138 provided on the detent 120, driving the latter against the tension of its spring, so as to permit the spring 118 to return the indicator 114 to its starting position against a stop 139. For a new line of computations or a new cycle of computing zones, the indicator ring would then advance step by step with each advancement of the state-controlling mechanism and the shaft 67. This will be true even if the number of zones are changed from time to time and the shaft 67 given different extents of movement to correspond inversely with the number of zones.

Considering briefly the operation of the device, the tappets 26 are placed at suitable intervals along the carriage 7 and in sufficient numbers requisite to give the desired number of computing zones for the several computing units. The number of computing zones or columns desired is ascertained before hand according to the type of work, and the disks 68 capable of controlling the number of zones selected are put in position on the shaft 67. For example, if nine zones are required, a disk having nine slots or zonal points is placed 120 125 130

for each computing unit. If eight zones are required, disks with each slots are used. The same is true of cycles of computation involving seven, six, and five zones, disks 5 with the corresponding number of slots being used. In all these cases, the tappet 91 is located in the proper slot in the bar 87 corresponding to the number of zones to be in action. That is, if nine zones are used, 10 it is placed so that it will give one-ninth of a revolution to the shaft 67, or, in other words, in the 90° slot, if eight zones are used and eight-slot disks, in the 90° slot, and so on, the idea being to complete a 15 revolution of the shaft 67 at the end of a cycle of computing zones. If a lesser number of zones than five is to be computed in, disks 68 having corresponding numbers of slots might be used, but in order to lessen 20 the number of disks in use, some of the other disks may be used, giving the shaft 67, however, rotation corresponding inversely to the number of zones to be computed in. For example, if four zones are required, the 25 eight-slot disks will be used for each computing unit. However, only every other slot will be considered a zone-determining point, and the shaft 67 be rotated a quarter of a revolution at each actuation of the general 30 operator by placing the tappet 91 in the 90° slot. For three zones, either the nine-slot disks or the six-slot disks can be used, giving, however, the shaft 67 a third of a revolution at each change in zone.

35 When the particular type of disk is decided upon corresponding to the number of zones, such zones as are to be subtracted in for any particular computing unit, will have one of the tappets 70 placed at the zone-controlling point with the extension projecting toward the left (Fig. 16). If a computing unit is to be neutral at any particular zone, the slot corresponding to this zone in the disk of the particular unit will have a 40 tappet 70 therein with the projection extending toward the right (Fig. 17). If, again, any particular computing unit is merely to add, there will be no tappet 70 located in the slot coming to the crucial 45 point at the determination of a zone, so that the mechanism will neither be set for subtraction nor neutral, and hence will be ready to add.

50 The machine is started at the beginning of a line with the indicator 114 at the first computing zone "1" at the line of sight, which may be determined by using the detent 120 as a pointer. Inasmuch as the shaft 67 always rotates in one direction in any of 55 the computing heads or units which are to be adding or to remain neutral in the initial zone, the tappets 70 would be properly positioned to have tripped the subtraction-setting mechanism; or swing the particular 60 zone-controlling roller 28 to a silent posi-

tion. The numeral keys are struck in the usual way typewriting the several digits of a number to be computed, which are set up either additively or subtractively in the nest of pins. The general operator is then actuated so that it runs up the computation in such of the computing units as are active. 70

On the forward stroke of the general operator, the dog 92 passes idly over the tappet 91 so as to be in a position to engage the 75 same on the return stroke, when it will move the bar 87 a certain distance against the tension of the spring 88, which distance will be inversely proportional to the number of computing zones. As the general operator 80 approaches the end of its return movement, carrying the dog 92 with it, the latter will be cammed by the disconnector 94 out of engagement with the tappet 91, permitting the latter with the bar 87, to return under 85 the pull of the spring 88. It is only during the driving movement of the rack bar 87 through the dog 92 engaging the tappet 91, that the shaft 67 is advanced. This advancement will bring the next active points or 90 slots of the series of disks 68 to the line of range, where if there are any tappets 70, they may be effective on the subtraction-setting mechanism or the zone-controlling-roller-silencing mechanism. It will thus be 95 evident that at each successive operation, the general operator advances the state-controlling mechanism one step corresponding to one zone, so that at the end of a line of writing or a predetermined series or group 100 of computations, the state-controlling mechanism will have completed a cycle.

The indicator 114 is advanced from the shaft 67 a step every time the shaft 67 and disks carried thereby are advanced a step. 105 The step of the indicator, however, may vary from that of the shaft 67, and merely moves a distance corresponding from one digit or zone-indicating number to another, so that at any time we may know in what 110 zone the mechanism is operating. Inasmuch as at the end of a cycle of computing zones, the state-controlling mechanism completes a revolution, the indicator will be tripped back to its initial position with the 115 "1" zone exhibited, by the tripper 137, so that the indicator will always be in synchronism with the state-controlling mechanism even though the indicator may not have had to go a complete revolution where 120 a lesser number than nine zones were in use.

In the case of an error, the error key 96 may be struck, which action, however, silences the drive to the state-controlling mechanism, so that the latter remains in 125 *status quo*, whereby after the error has been eliminated, the same computation can take place as was originally intended. The error key simultaneously starts the general operator into motion through the arm 111, so 130

that we are assured that if any of the computing units were to have subtracted, the subtraction-setting mechanism will have been re-actuated to perform such functions as are necessary in a complementary subtraction operation prior to the setting up of the digits, as, for example, the setting of the "9" pins. It will be noted in an action of this type, that the subtraction tappet 70 5 remains under its pin 72, so as to maintain the subtraction key and thus the latch 49 in its tripped position. Under normal circumstances, the supplementary latch 56 catches and holds the subtraction bar 45, 10 inasmuch as the subtraction key 52, and hence the latch 49, are not released until the general operator, near the end of its stroke, advances the subtraction tappet 70 from beneath its pin 72.

20 The general operator first clears the tappet 70 from the subtraction mechanism and then, on completing its stroke, silences the latch 56, so that, if necessary, the mechanism of a particular computing unit can once more be set for subtraction, that is, 25 even for two zones in successive subtracting zones for a particular computing unit. This is repeated for a given series of computations, for example, line after line, the state-controlling mechanism automatically governing the activity and character of activity of each and all of the computing units according to a predetermined sequence for which the mechanism has been set beforehand. The operative then has merely to 30 bring into play the general operator at each computing zone, to get the requisite character and automatic succession of varying operations.

35 40 Variations may be resorted to within the scope of the invention, and portions of the improvements may be used without others.

Having thus described my invention, I claim:

45 1. The combination with a computing head comprising computing wheels, of a general operator for simultaneously turning said wheels, and a state-controlling mechanism adapted to be advanced by said general operator step by step to govern the 50 activity and character of activity of said computing head according to a predetermined plan.

55 2. The combination with a computing head comprising computing wheels, of a drive for said computing head adapted to simultaneously turn said wheels, settable devices selectively adjustable to determine whether adding or subtracting in said computing head shall be effected by said drive, 60 denomination-selecting mechanism, a general operator, and mechanism operated from said general operator and acting to adjust said settable devices, so as to determine the 65 character of computation carried on by said

computing head and to adjust said denomination-selecting mechanism to determine the activity thereof.

3. The combination with a computing head comprising computing wheels, of a 70 drive for said computing head including devices adapted to turn said wheels simultaneously, indexing mechanism for determining the extent of movement of said devices, adjusting means to determine whether the devices shall act for addition or subtraction, a general operator, and state-controlling mechanism controlled in turn from said general operator, and acting to manipulate said adjusting means so as to vary the 80 computing character of action of said devices.

4. The combination with a computing head including a series of computing wheels, 85 of a drive for said computing head including elements adapted to be driven simultaneously and always in the same direction, indexing mechanism for determining the extents of movement of the elements of said drive, so that they may effect either addition 90 or subtraction, adjusting means for said indexing mechanism to determine whether the movements shall effect addition or subtraction, a general operator always effective to drive in one direction only, and a state-controlling mechanism actuated by said general operator at each active action thereof, to be capable of operating said adjusting means so as to determine whether the computation run into said computing head shall be made 100 additively or subtractively.

5. The combination with a computing mechanism including computing wheels, indexing mechanism, denomination-selecting mechanism, and a general operator always effective in one direction only, of an automatic state-controlling mechanism driven on the idle stroke thereof, devices operated by said automatic mechanism for adjusting said denomination-selecting mechanism between silent and active positions, and devices also operated by said automatic mechanism for adjusting said indexing mechanism to set up computations additively or subtractively.

6. The combination with a computing mechanism including computing wheels and a general operator, of state-controlling mechanism actuated from said general operator step by step to give a predetermined sequence of states of said computing mechanism for each successive computing zone.

7. The combination with a plurality of computing units, of a general operator common to all said computing units, and state-controlling mechanism driven from said general operator and arranged to afford a predetermined sequence of concomitant states for all said computing units in a given cycle of computing operations.

8. In a combined typewriting and computing machine, the combination with a computing unit, of a subtraction-setting device therefor, a spring for operating said subtraction-setting device, a bar for setting said device to subtraction, a general operator for operating said unit and returning said device to addition, and a catch adapted to be set to hold said device effective during the idle stroke of the operator and then releasing it.

9. The combination with a plurality of computing units, each comprising computing wheels and devices on which digits are adapted to be set up, of a general operator common to said computing units to carry the set-up digits into the wheels in all the units simultaneously, and a single state-controlling mechanism for all of said computing units effective to set said computing units selectively for addition or subtraction either in agreement with or in opposition to each other.

10. The combination with a computing mechanism including one or more computing units, of a predetermined sequence state-controlling mechanism advanced step by step under the control of said computing mechanism at each running up of a computation in a computing unit, to determine the activity of computing units in successive computing zones and the state or character of computing operation of the computing units in such zones.

11. The combination with a computing mechanism including a plurality of computing units, of a general operator common to all the units, a predetermined-sequence state-controlling mechanism advanced step by step under the control of said computing mechanism at each running up of a computation in a computing unit by said operator, to determine the activity of computing units in successive computing zones and the state or character of computing operation of the computing units in such zones, said state-controlling mechanism including parts selectively alterable independently for each unit to vary the predetermined sequence or order of states which it controls.

12. The combination with a computing mechanism including one or more computing units arranged to compute in successive computing zones, and a general operator, of state-controlling mechanism for determining the activity of the computing units for successive computing zones, and a zone indicator driven from said general operator and controlled by said state-controlling mechanism adapted to point out the particular zone in which a computation is being carried on at any particular moment.

13. The combination with a computing mechanism including a general operator which at each normal operation determines

a computing action for a given computing zone, of a zone-indicator driven from said general operator and arranged to designate the particular computing zone in which a computing operation is taking place at any particular time.

14. The combination with a computing mechanism, of a state-controlling mechanism for governing automatically the successive actions of said computing mechanism for a given cycle of computing zones, said state-controlling mechanism having a variable advancement according to the number of zones in a cycle of computing operations, and a zone-indicator driven from said state-controlling mechanism to advance step by step for zone for zone irrespective of the extent of advancement of said state-controlling mechanism for each zone.

15. The combination with a computing mechanism, of a state-controlling mechanism for governing said computing mechanism according to a predetermined sequence of computing actions for a cycle of computing zones, a zone-indicator for designating which zone in the cycle is in action at any particular time, and a differential drive for said zone-indicator advancing the same step by step to keep pace with the designation of the particular zones in the cycle independent of the number of zones in the cycle, which may vary.

16. The combination with a computing mechanism, of a state-controlling mechanism for governing said computing mechanism according to a predetermined sequence of computing actions for a cycle of computing zones, a zone-indicator for designating which zone in the cycle is in action at any particular time, and a uniform-stroke drive acting on said zone-indicator and operated from said state-controlling mechanism to enable said zone-indicator to keep pace with the zones of said state-controlling mechanism while the latter may vary in its action according to the number of zones desired in a cycle of computing operations.

17. The combination with a computing mechanism, of a state-controlling mechanism for governing said computing mechanism, a differential drive for variably advancing said state-controlling mechanism, a zone-indicator for designating the particular zone in action at any particular time, and a drive acting uniformly on said zone-indicator to advance the same zone by zone for the differential advancement of said state-controlling mechanism zone by zone.

18. The combination with a computing mechanism, of a state-controlling mechanism for governing said computing mechanism according to a predetermined sequence of computing actions for a cycle of computing zones, a zone-indicator for designating which zone in the cycle is in action at any particu-

lar time, said state-controlling mechanism completing a cycle in correspondence with the number of zones desired in a cycle of computing operations, a uniformly-acting 5 drive for said zone-indicator advancing the same zone by zone for differential zonal advancements of said state-controlling mechanism, said zone-indicator being fixed in its capacity of zonal indication, and automatic 10 means for synchronizing the actions of said state-controlling mechanism and said zone-indicator for each cycle of computing zones.

19. The combination with a computing mechanism, of a continuously-advancing 15 state-controlling mechanism for said computing mechanism arranged to give a given sequence of computing operations for a cycle of computing zones, an intermittently advancing zone-indicator keeping pace with 20 said state-controlling mechanism to designate the particular zone in action at any given time, and automatic means for returning said zone-indicator to a starting position as said state-controlling mechanism completes a cycle of zones and reaches a starting 25 position.

20. The combination with a computing mechanism, of a zone-indicator for designating which one in a cycle of computing zones 30 is in action at any particular time, driving means for advancing said zone-indicator step by step up to any limited number of zones desired in a cycle, and automatic means for returning said zone-indicator to a starting 35 position when the predetermined number of zones in the cycle has been reached.

21. The combination with a computing mechanism, of a zone-indicator for designating which zone in a cycle of computing zones 40 is in action at any particular time, driving means for advancing said zone-indicator step by step up to any limited number of zones desired in a cycle, automatic means for returning said zone-indicator to a starting position when the predetermined number of 45 zones in the cycle has been reached, said automatic means comprising a spring tensioned during the advancing movement of said zone-indicator, a detent for said zone-indicator, and a trip for said detent.

22. The combination with a computing mechanism, of a zone-indicator for designating the particular one of a cycle of zones in action for said computing mechanism, a variably advanced member, an actuator for advancing said indicator, and connecting means 55 automatically joining said actuator to move with said variably advanced member for a uniform period at each advancing movement 60 of said member so as to advance said indicator always a uniform amount.

23. The combination with a computing mechanism, of an indicator for designating which one of a cycle of zones is in action at 65 any particular instant, a variably advanced

member, an actuator for advancing said indicator, a clutch for connecting said actuator with said variably advanced member, and automatic mechanism for disconnecting said actuator from said variably advanced member after a predetermined movement therewith. 70

24. The combination with computing mechanism, of an indicator for indicating which zone is in action for said computing mechanism, a 75 member having a variable advancement, an actuator for advancing said indicator uniformly, a clutch for connecting said actuator with said member, a spring normally tending to render said clutch effective, and camming means for silencing said clutch after a predetermined movement of said actuator with said member. 80

25. The combination with a computing mechanism, of a zone-indicator for designating which one of a series of zones is in action in the actions of said computing mechanism, a pawl-and-ratchet mechanism for advancing said zone-indicator, an actuator for said pawl-and-ratchet mechanism, a member for 85 driving said actuator, a clutch for connecting said actuator with said member, a spring tending to cause said clutch to act, a cam for silencing said clutch after a predetermined movement of said actuator with said member, and guiding means for enabling said clutch to act for a subsequent operation of said member. 90

26. The combination with a computing mechanism, of a zone-indicator for designating which zone of a particular cycle of computing zones is in action at any given time, an actuator for advancing said zone-indicator zone by zone, a variably driven member having at times a greater advancement or 100 movement than necessary to advance said indicator for one zone, and automatic mechanism for connecting and disconnecting said actuator to and from said member so that said actuator will have a movement merely 105 adequate to advance said indicator for one zone. 110

27. The combination with a computing mechanism including a general operator, of a state-controlling mechanism for said computing mechanism, and a differential driving connection between said general operator and said state-controlling mechanism whereby said state-controlling mechanism may be driven from said general operator during 115 120 but a portion of the movement thereof.

28. The combination with a computing mechanism including a general operator, of a state-controlling mechanism for governing zone by zone the character of action of said 125 computing mechanism, and a variably driving connection between said general operator and said state-controlling mechanism adjustable to advance said state-controlling mechanism different amounts for the same type of 130

action of said general operator and for different numbers of zones in a cycle of computing operations.

29. The combination with a computing mechanism including a general operator, of a state-controlling mechanism for governing the action of said computing mechanism including a shaft, and a driving connection between said general operator and said state-controlling mechanism including a gear on said shaft, a rack bar driving said gear, and a single-acting pawl connected to said general operator for driving said rack bar on one stroke of said general operator.
- 15 30. The combination with a computing mechanism including a general operator, of a state-controlling mechanism for governing said computing mechanism for a cycle of computing zones, and driving connections for advancing said state-controlling mechanism zone by zone for successive operations of said general operator including a driving member, a tappet adjustable to various points along said driving member, and a pawl on said general operator for engaging said tappet to operate said driving member variable distances according to the position of said tappet.

31. The combination with a computing mechanism including a general operator, of a state-controlling mechanism for governing the action of said computing mechanism according to a predetermined sequence of operations for a cycle of computing zones, and a variable drive connection between said general operator and said state-controlling mechanism including a tappet adjustable to various positions to vary the extent of advancement of said state-controlling mechanism for an operation of said general operator.

32. The combination with a computing mechanism including a general operator, of a state-controlling mechanism for governing the computing operations of said computing mechanism for a cycle of computing zones, and connections between said state-controlling mechanism and said general operator enforcing the concomitant completion of a cycle of computing operations of said computing mechanism by said general operator, and a cycle of state-controlling actions for a cycle of zones by said state-controlling mechanism.

55 33. The combination with a computing mechanism including a general operator, of a state-controlling mechanism for governing the computing operations of said computing mechanism for a cycle of computing zones, and connections between said state-controlling mechanism and said general operator enforcing the concomitant completion of a cycle of computing operations of said computing mechanism by said general operator, and a cycle of state-controlling actions for a

cycle of zones by said state-controlling mechanism, said connections being variable to correspond with a variation in the number of computing zones desired in a cycle.

34. The combination with a computing mechanism including a device settable to cause it to subtract, of a general operator for said computing mechanism, adapted to reset said device so that addition will be effected, an error key for eliminating a false manipulation of said computing mechanism, and connections for enabling said error key to automatically start said general operator into motion at an actuation of said error key.

35. The combination with a computing mechanism including a device settable to cause it to subtract, of a general operator for said computing mechanism, adapted to reset said device so that addition will be effected, an error key for eliminating a false manipulation of said computing mechanism, a motor for driving said general operator, and automatic connections controllable from said error key for causing a driving action of said general operator by said motor at an actuation of said error key.

36. The combination with a computing mechanism including settable digit pins, of a device for resetting said pins, a bar operable to cause the pins to be set to effect subtraction, a motor for effecting computations by the set pins and adapted to restore said bar, so that addition will be effected, keys for setting said pins, and an error key for simultaneously resetting said pins and starting the motor.

37. The combination with a computing mechanism including settable digit pins, of a device for resetting said pins, a bar operable to cause the pins to be set to effect subtraction, a motor for effecting computations and adapted to restore said bar, so that addition will be effected, keys for setting said pins, an error key for simultaneously resetting said pins and starting the motor, a state-setting device, a connection whereby said motor drives said state-setting device, and means for disabling said connection by operation of said error key.

38. The combination with computing mechanism including a device settable to cause it to subtract, of a motor for driving said computing mechanism, a general operator through which said driving is effected, said operator adapted to reset said device so that addition will be effected, error-correcting mechanism for said computing mechanism, a normally-open clutch between said motor and said computing mechanism, a pin for maintaining said clutch open and inactive, and a trip for said pin operable from said error-correcting mechanism to start the operator to reset said device.

39. The combination with computing mechanism, of state-controlling mechanism for

130

varying the computing action of said computing mechanism for a series of computing zones, error-correcting mechanism for said computing mechanism, and connections rendering said state-controlling mechanism controllable from said error-correcting mechanism.

40. The combination with one or more computing units, of a general operator for 10 said computing units, error-correcting mechanism for said computing units, state-controlling mechanism for governing said computing mechanism according to a predetermined cycle, driving means operable from 15 said general operator for advancing said state-controlling mechanism at an actuation of said general operator, and silencing means dominated by said error-correcting mechanism for preventing an advancing of 20 said state-controlling mechanism at the time of an action of said error-correcting mechanism.

41. The combination with a plurality of computing units, of a state-control shaft for 25 determining how said units shall effect computations and adapted to be rotated in variable fractions, an indicator on said shaft, a pawl for driving said indicator, a lever on said shaft for driving said pawl, a clutch 30 between the lever and the shaft, and means for making the clutch effective and ineffective to cause the lever to give a uniform throw to the pawl irrespective of the fraction through which the shaft turns.

35. 42. The combination with one or more computing units, of a general operator for 35 said computing units, state-controlling mechanism for said computing units, advancing means for said state-controlling mechanism 40 operating at the actuation of said general operator, and silencing means for said advancing means effective to permit an ineffectual action of said general operator with regard to said state-controlling mechanism.

45. 43. The combination with one or more computing units, of a general operator for 45 said computing units, state-controlling mechanism for governing the character of computation carried on by said computing units 50 according to a predetermined sequence, connections for advancing said state-controlling mechanism with the operation of said general operator, a hand lever for silencing said connections so as to prevent an advancement 55 of said state-controlling mechanism with an actuation of said general operator, and error-correcting mechanism for said computing units connected to silence said connections so as to prevent an advancement of 60 said state-controlling mechanism.

44. The combination with a computing mechanism, of state-controlling mechanism for said computing mechanism including a revolute shaft, disks adapted to be mounted

on said shaft and adapted to be peripherally 65 divisible into zonal points according to the number of zones desired in a cycle of computing operations governed by said state-controlling mechanism, and driving means for said shaft adjustable to fractionally rotate the same inversely as the number of computing zones desired in a cycle of computing operations.

45. The combination with a computing mechanism, of a state-controlling mechanism 75 for said computing mechanism, a driving member for advancing said state-controlling mechanism, a tappet on said driving member adjustable at various points therealong according to the extent of advancement 80 of said state-controlling mechanism desired, and a dog engaging said tappet to operate said driving member.

46. The combination with a computing mechanism, of a state-controlling mechanism 85 for said computing mechanism, a driving member for advancing said state-controlling mechanism, a tappet on said driving member adjustable at various points therealong according to the extent of advancement 90 of said state-controlling mechanism desired, a dog engaging said tappet to operate said driving member, and silencing means for holding said dog clear of said tappet to prevent an advancing movement of said state-controlling mechanism.

47. The combination with a computing mechanism, of a state-controlling mechanism 100 for said computing mechanism, a driving member for said state-controlling mechanism, a one-way-acting connection between said driving member and said state-controlling mechanism, a spring for operating said driving member in one direction, and a one-way-acting dog and tappet for actuating 105 said driving member in the opposite direction.

48. The combination with a computing mechanism, of a state-controlling mechanism 110 for said computing mechanism, a driving member for said state-controlling mechanism, a one-way-acting connection between said driving member and said state-controlling mechanism, a spring for operating said driving member in one direction, a one-way-acting dog and tappet for actuating said driving member in the opposite direction, and means for tripping said dog and tappet 115 from each other after a predetermined movement of said driving member.

49. The combination with a computing mechanism, of a state-controlling mechanism 120 for said computing mechanism, and driving means for said state-controlling mechanism including a bar having positioning points at fractional intervals of the movement of said bar from one-ninth to the

- whole movement thereof, and a tappet adjustably mounted at any one of said positioning points to determine the extent of advancing movement of said state-controlling mechanism by said driving means.
50. The combination with a computing mechanism, of a state-controlling mechanism for said computing mechanism having a cycle of step movements corresponding to a cycle of computing zones for said computing mechanism, and driving means for said state-controlling mechanism having a movement limited to that corresponding to the completion of a cycle by said state-controlling mechanism, and including a tappet adjustable at points corresponding to one-ninth, one-eighth, one-seventh, one-sixth, one-fifth, one-fourth, one-third, one-half, and one whole of the complete movement of said driving means, whereby the extent of advancing movement of said state-controlling mechanism and thus the number of movements of advancement to complete a cycle may be determined.
51. A state-controlling mechanism comprising a shaft, a plurality of disks adapted to be interchangeably mounted on said shaft, said disks having variously arranged slots therein, and tappets adjustably mounted in said slots in variously effective positions.
52. A state-controlling mechanism comprising a shaft, a disk detachably and replaceably mounted on said shaft, a catch for locking said disk on said shaft, said disk having a plurality of slots therein corresponding to zonal points or stopping points of said state-controlling mechanism, and a plurality of tappets formed to project on one side or the other of said disk, and detachably and adjustably mounted in said slots.
53. The combination with a state-control mechanism including a shaft, of devices adapted to be variably mounted on said shaft to determine how the states shall be controlled, a general operator for effecting computations, and a dog settable on said operator to turn the shaft according to the mounting of the devices.
54. The combination with a state-control mechanism including a shaft, of devices adapted to be variably mounted on said shaft to determine how the states shall be controlled, a general operator for effecting computations, a dog settable relatively to said operator to turn the shaft according to the mounting of the devices, computing devices on which said state control is effective, a manual state control for said computing devices, and means for making said dog ineffective during an operation of the operator.
55. The combination with a computing unit, of a general operator for said computing unit, state-controlling mechanism for said computing unit, driving mechanism for said state-controlling mechanism actuated from said general operator, manual means for setting said state-controlling mechanism to subtraction, and a single-acting silencing means for maintaining said first-named driving mechanism inactive for a single action of said general operator.
56. The combination with a computing mechanism, of a general operator for said computing mechanism, a subtraction-setting mechanism for said computing mechanism, and automatic means controlled from said general operator for actuating said subtraction-setting mechanism at predetermined so intervals so as to afford subtracting actions of said computing mechanism for one or more computing zones in a given cycle of computing zones.
57. The combination with a computing mechanism, of a state-controlling mechanism for said computing mechanism, a driving member for advancing said state-controlling mechanism and having a uniform stroke, variously-formed devices adjustable on said state-controlling mechanism adapted to be effective at various points of arrest thereof, and a tappet adjustable on said driving member to variably advance said state-controlling mechanism according to the devices thereon.
58. The combination with a computing mechanism, of a state-controlling mechanism for said computing mechanism, a driving member having a uniform stroke for driving said computing mechanism and adapted to advance said state-controlling mechanism, a shaft forming part of said state-controlling mechanism, devices adapted to be mounted on said shaft to be effective at various points in the rotation thereof, to determine how said state-controlling mechanism shall effect its control, a pinion on said shaft, a rack engaging said pinion and adapted to move with said driving member, and a tappet adjustable on said driving member to vary the throw of said rack.
59. The combination with a plurality of gang-driven computing units, of a general operator for said computing units, and state-controlling mechanism having separately settable units individual to each computing unit, connected to be driven at each computing action of said general operator.
60. The combination with a plurality of computing units, of a state-controlling mechanism for said computing units, a general operator for said computing units, said state-controlling mechanism having units universal to each computing unit and constructed so as to limit the computing operations of the computing units to a given cycle of repeated computations of predetermined

relative character and corresponding to a series of computing zones forming a cycle, driving means operated concomitantly with the operation of said general operator to 5 advance said state-controlling mechanism for a new zone with each running up of a computation into said computing units by said general operator, means for making said driving means ineffective, and devices 10 operable manually to selectively determine for each unit whether it shall add or subtract.

61. The combination with a plurality of computing units, of a state-control for determining how said units shall compute and 15 including a shaft adapted to be rotated in variable fractions of a revolution, an indicator adapted to be driven by said shaft, and means whereby said indicator always turns 20 a uniform amount and returns the indicator to unity at the completion of a revolution of the shaft.

62. The combination with a plurality of computing heads, of a state-control shaft 25 always revolving in the same direction and comprising devices settable to bring about various states in the plurality of zones represented by said heads, an indicator adapted to indicate the maximum number of zones 30 possible, and means whereby said state-control shaft sets said indicator to show the number of the active zone.

63. The combination with a computing head, of a general operator for said head, a 35 plurality of denomination-selectors for said head adapted to be effective or ineffective, a device associated with each denomination-selector for making it effective or ineffective in any zone, a series of controlling members 40 adapted to be selectively set for each of said devices, and a common bar operable by said general operator for variably making said members effective at each actuation of the general operator.

64. The combination with a plurality of computing heads, of a plurality of sets of jacks, one set for each head, a plurality of denominational selectors to operate said jacks and thus control the denominational 50 selections of said heads, and controlling means for selectively governing the effectiveness of said denominational selectors, to engage, individually, one or more of said several sets of jacks.

65. The combination with a plurality of computing heads, of a plurality of sets of jacks, one set for each head, a series of controlling denominational-selectors to cooperate with said jacks in effecting denominational 55 selections for the several computing heads, and automatic controlling means for governing the active relation of said selectors to said jacks in each of a plurality of zones, so as to determine whether one or

more of said heads shall be in action in particular zones according to a predetermined plan.

66. The combination with typewriting mechanism including a carriage traveling to determine the successive typewriting zones, 70 of a computing mechanism including a plurality of computing units, denominational-selecting mechanism actuatable from said carriage to coördinate the denominational selections in said computing mechanism with the 75 digit columns of the digits as written by said typewriting mechanism, and a central control governed by said computing mechanism for determining the activity of said denominational-selecting mechanism for the several 80 computing units, so as to determine which and how many of the computing units shall be in action for each typewriting zone.

67. The combination with a computing mechanism including a plurality of computing units, of a typewriting mechanism including a traveling carriage connected to control denominational selections in said computing units for several zones as determined by the travel of said carriage, and a 90 central control of the activity of the computing units for the several zones independent of the control from said carriage, and dominated by said computing mechanism to cause the activity of the computing units to 95 agree with a predetermined plan for the several combined typewriting and computing zones as determined by the travel of said carriage.

68. The combination with a plurality of computing heads, of a general operator common to said heads, denomination-selectors for said heads adapted to be effective or ineffective, a device associated with each head for making the denomination-selector in any 100 zone effective or ineffective, a series of controlling tappets adapted to be selectively set for each of said devices, a common member operable by said general operator for variably making said tappets effective at each 110 actuation of the general operator, and a device settable to make said general operator ineffective on said member at an actuation thereof.

69. The combination with a plurality of computing units, of a denomination-selector for each unit, a general operator for operating said units, a link for each selector, a connection operated by each link adapted to determine whether its selector shall be effective, a single member common to said links for selectively operating them, and means whereby said general operator operates said member to vary the effectiveness of the denomination-selectors individually. 115 120 125

70. The combination with a computing unit, of a plurality of denomination-selectors adapted to make said unit effective to

compute, a traveling carriage adapted to select the zones in which the computing is done by said selectors, a general operator for effecting computations in said unit, a link for 5 each selector, a connection operated by each link adapted to determine whether its selector shall be effective or ineffective, connections whereby said unit, when effective, normally adds connections including a link for causing it to subtract, and a member comprising a plurality of settable devices adapted to determine for each zone whether said unit, if computing, shall add or subtract.

HORATIO WHITING.
